MEAT SLICER

Joseph Folk, La Porte, Ind., assignor to U. S. Slicing Machine Company, La Porte, Ind., a corporation of Indiana

Application October 14, 1932, Serial No. 637,756

5 Claims. (Cl. 146—102)

The present invention relates to slicing machines and particularly to the type of slicing machine in which the carriage and knife are moved relative to each other by manual means, the knife being driven independently of the carriage.

One object of this invention is to provide a releasable carriage mounting whereby the carriage may be removed for inspection, cleaning, or the like and replaced with the minimum amount of effort in juxtaposition with the guides of the slicing machine.

Another object of this invention relates to a novel form of releasable connection between a bearing slidably mounted relative to the knife and a slicing machine carriage upon which the substance is to be supported.

Another object of this invention resides in a novel form of slice-receiving tray which can be quickly cleaned if and when desired.

20 Another object of this invention is to provide an extension for the carriage adapted to extend the supporting surface for the substance in a direction away from the cutting plane of the knife whereby when a long substance is to be sliced, 25 the supporting surface of the carriage can be extended to adequately support the same. This extension for the carriage can be moved into an inoperative position entirely out of the way of the operator.

30 Other objects of this invention will appear hereinafter as the description thereof proceeds, the novel features, arrangements, and combinations being clearly set forth in the appended claims.

35 In the drawings:

Fig. 1 represents a front elevational view of a slicing machine embodying my invention;

Fig. 2 is a side elevational view looking from the right in Fig. 1;

40 Fig. 3 is a side elevational view of the slicing machine looking from the left in Fig. 1;

Fig. 4 is a plan view of the slicing machine shown in Figs. 1 to 3 inclusive;

45 Fig. 5 is a bottom plan view of the bearing member which supports the carriage and showing the releasable connection between the support and the carriage;

Fig. 6 is a detail view of part of the detachable connection between the carriage and bearing therefor;

50 Fig. 7 is a cross-section taken substantially along the line 7—7 of Fig. 2 with the clamp in engagement with a substance being sliced and with the auxiliary support for the substance extended;

Fig. 8 shows a modified releasable mounting for the carriage;

Fig. 9 is a bottom plan view of the mechanism shown in Fig. 8 with a part thereof in section for the sake of clearness;

The reference character 15 represents the base of a slicing machine and 16 and 17 represent guides upon which a bearing member 18 slides. The bearing member 18 as is perhaps best illustrated in Figs. 2 and 5 has a sleeve portion 19 embracing the guide 17 and a flanged roller 20 which rides on the upper surface of the guide 16. The guide 17 is provided with a cover portion 21 which extends over the entire operative surface of said guide and is integrally formed with the brackets which support the guide 17. The portion of the cover 21 extends down between the cutting plane of the knife and the guide 17 to prevent foreign matter and slices from contacting with the guide.

The slicing machine carriage is indicated by the reference character 22 and has an upper substance support which is substantially V-shaped in cross-section with both substance engaging surfaces sloping upwardly from a horizontal plane as is clearly illustrated in Fig. 2. This carriage is provided with uprights 23 and 24 which slidably support the clamp 25 for movement toward and from the supporting surface of said carriage 22. The uprights 23 and 24 are carried by a bearing member 26 arranged partially beneath the substance support and guided by the guides 27 and 28 which extend substantially perpendicularly to the cutting plane of the knife 29 which is driven by the motor 50 by any suitable gearing such as the belt 30 illustrated in dotted lines in Fig. 3. The clamp can be advanced toward the cutting plane of the knife by manual pressure applied to the handle 31 thereof or can be fed by spring pressure acting on the bearing member 26.

The slicing machine is provided with a gauge plate 32 which has the substance engaging surface thereof extending substantially parallel to the cutting plane of the knife for gauging the thickness of the slices to be formed. The knife 29 is recessed at 33 as is clearly illustrated in Figs. 2 and 4, and a guard plate 34 having ribs 35 thereon is arranged within the recess 33 and has the substance engaging portion thereof which includes the surfaces of said ribs arranged substantially in the cutting plane of the knife when the guard plate is in operative position.

The guard plate as illustrated in Figs. 2 and 4 has an enlarged bearing portion 36 thereon at

the lower end thereof having recesses at the opposite ends thereof into which the adjustable pivots 38 extend. The adjustable pivots 38 are carried by the bracket 39, secured by the bolts 40 and locating pins 41 to the portion of the cover 21 which extends downwardly between the cutting plane of the knife and the guide 17. Thus the guard plate can be pivoted toward and away from the cutting plane of the knife to permit the same to be cleaned or to permit the cleaning of the knife. This guard plate is not claimed herein, but is claimed in applicant's co-pending application Serial No. 719,692 filed April 9, 1934.

15. The slicing knife has the upper and rear edges thereof covered by the circular hollow guard 49 attached in any desired manner to the frame of the slicing machine. The knife is driven by the motor 50 which is rockably mounted on the bracket 51 which in turn is pivoted at 52 to the knife supporting bracket 53. The belt 30 is tensioned by an adjusting screw 54 which passes through the arm 55 on the bracket 51. The adjusting screw engages a portion of the knife supporting bracket 53 and when turned in a right hand direction moves the bracket 51 in a counter-clockwise direction to impart additional tension to the belt 30. A deflector 56 is releasably secured to the knife bracket 53 by means of 30 thumb screws 57 passing through suitable slots 58 formed in the edge of the deflector.

A slice-receiving tray 59 is secured to the base in a position to receive the slices as they are formed and as will be noted in Fig. 3, extends 35 beneath the center of the knife and a substantial distance toward the rear thereof. The tray 59 is provided with a peripheral bead 60 which prevents paper and the like from sliding off the tray. There is a gap in the bead 60 at 61 to permit the operator to wipe the scraps off the tray 59 through 40 this gap in the bead. At the same time, it does not detract from the usefulness of the bead for the purposes intended. The bead extends upwardly around the knife bracket as at 62 and the 45 knife supporting bracket 53 has a portion 63 thereof overhanging the bead 62 so that material cannot fall readily between the tray 59 and the bracket 53.

50. Referring now particularly to Figs. 2, 5, and 6, it will be noted that the bearing member 18 is provided with two laterally extending conically pointed pins 64 threaded into the bearing member 18 and held in place by lock nuts 65. The pins 64 have the conical points thereof adapted to be 55 releasably received within conical openings in the plates 66 which are secured to a vertically extending surface near the bottom of the substance support 22 as clearly indicated in Fig. 2, the fastening means comprising screws 67. At the opposite side of the bearing member 18, there is secured an upwardly extending plate 68 secured thereto by a screw 69. This plate is illustrated in perspective in Fig. 6, and has a notched portion 70 which terminates at the bottom thereof in a circular recess 71 having a beveled seat 72 adapted to cooperate with a beveled seat 73 on a clamping screw 74 which is threaded into the support 22. The screw is operated by means of the lever 75 which is slidably mounted in the head of the screw to extend either to one side or the other thereof. It is obvious that the entire carriage can be quickly released merely by releasing the screw 74 and without the necessity of entirely removing the screw since the shank of the screw 74 can pass upwardly through the notch 70 in the plate

68 prior to the time when the screw 74 is entirely released from the carriage 22. Thus, I have provided a very simple and efficient means whereby the carriage can be quickly removed from the bearing 18. The bearing and carriage have co-operating machine surfaces 16 so that the carriage will always be mounted at the same elevation and with the clamping means which has just been described, it is obvious that the carriage will always be located in the proper operative relation with respect to the cutting plane of the knife when the carriage is in place and properly clamped.

The carriage is provided at the side thereof remote from the cutting plane of the knife with a 15 downwardly extending skirt 11 having an opening therein to receive the rods 18 which are arranged parallel to each other and to the supporting surface of the substance support. The rods are connected by a substance supporting member 19 which has the upper edge thereof substantially in the same plane as the upper supporting surface of the substance support. Additional lugs 80 are formed on the under side of the carriage and are provided with bearings through which the rods 18 also extend to provide additional support therefor, and to prevent tilting movement thereof in a vertical direction. Pins 81 extending through the ends of the rods releasably hold the rods in place and prevent separation of the rods and substance supporting member 19 from the supporting carriage except if and when desired. It is obvious that when the rods 18 are moved to the left in Fig. 7, the substance supporting member 19 will lie closely adjacent the edge of the substance support and will be out of the way of the operator. This additional support is for use with substances which are relatively long and which normally would overlie the edge of the ordinary substance support without making it necessary to have a permanent extension for the substance support, which extension ordinarily would be in the way and detract from the efficiency of the machine.

45. In Figs. 8, and 9, I have shown a modified arrangement for holding the substance supporting carriage 22' releasably in place on the bearing 18'. This means comprises a pair of downwardly extending pins 82 having enlarged heads 83 with conical seats 84 and tapered noses 85. These pins are adapted to be arranged within enlarged openings 86 having conical seats 87 surrounding the lower edges of the opening. The bearing member 18' is provided with an upwardly and outwardly extending lug 87' and a clamping screw 88 provided with an operating knob 89 is threaded through a downwardly extending lug 90 on the carriage 22'. Cooperating bearing surfaces on the carriage and bearing are indicated at 91 and when the carriage is placed on the bearing 18' with the bearing surfaces in contact, and the pins 82 extending through the openings 86, the screw 88 may be tightened against the lug 87' by operating the knob 89 whereby the conical seats 84 and 87 are drawn firmly into engagement with each other and cause wedging action which draws the carriage firmly against the bearing 18'. The same is true of the lug 87' and the head of the screw 88 since the lower inclined surface of the lug 87' causes the screw 88 to move downwardly as the clamping pressure is applied and consequently this pressure is transmitted to the carriage 22' in a downward direction so that the carriage is firmly held in operative position on the bearing and in proper position with respect thereto.

so that when the carriage is moved past the knife, the carriage will not strike the knife but will be as is the usual practice closely adjacent the cutting plane of the knife to support the substance while the substance is being sliced.

The position of the gauge plate is adjusted by means of the operating knob 92 illustrated in Fig. 1 which knob is threaded on the end of the rod 93 secured to the gauge plate 32.

10 In Figs. 1, 2, 3, 4, and 8, I have shown the upper portion of the guard 21 flat on top and to this flat portion, there is secured a plate 120. This plate which may be formed as an integral portion of the guard if desired, is adapted to support a substance when the carriage of the slicing machine is removed from the reciprocating frame to which the carriage is removably connected. Screws 121 or the like may be used in securing the plate to the guard. This arrangement is particularly useful when it is desired to remove the rind from bacon or to cut the crusts from a loaf of bread. The plate 120 while relatively narrow is of sufficient width to adequately support the substance during the slicing operation, it being understood that the substance is pressed against the gauging plate by hand, and reciprocated along the plate by manual pressure applied thereto parallel to the cutting plane of the knife.

30 Obviously those skilled in the art to which this invention pertains may make various changes in the particular arrangement of the parts shown in the accompanying drawings without departing from the spirit of this invention and therefore 35 I do not wish to be limited except as hereinafter set forth in the appended claims.

Having thus fully described my invention, what I claim as new and desire to obtain by United States Letters Patent is:

40 1. A slicing machine comprising a bearing support for a carriage, a carriage adapted to be releasably supported on said bearing and having cooperating bearing surfaces thereon engaging corresponding bearing surfaces on said bearing, 45 projecting pins on said bearing extending substantially parallel to said cooperating bearing surfaces, downwardly extending portions on said carriage having recesses to receive said pins, and clamping means acting in the general direction 50 in which said pins extend for drawing the downwardly extending projections on said carriage firmly into engagement with said pins for preventing upward movement of said carriage relative to said bearing, said clamping means comprising a slotted plate on said bearing and a clamping screw on said carriage, the shank of which is adapted to enter said slot and the head of which is adapted to engage a cooperating seat on said plate and prevent movement of said 55 shank out of said slot and to prevent movement of said carriage away from said bearing.

2. In a slicing machine, the combination with a bearing for the substance carriage having a plurality of upwardly extending openings, a substance carriage having downwardly extending projections thereon extending into said openings, beveled seats on the under side of said bearing surrounding said openings, and cooperating sim-

ilarly formed seats on said downwardly extending projections for cooperating with the seats surrounding said openings to prevent upward movement of said carriage away from said bearing when said seats are in engagement with each other, and clamping means acting in a direction substantially parallel to the meeting surfaces of the carriage and bearing, said last mentioned means being mounted on said carriage and cooperating with a sloping surface on said bearing 10 for drawing said support and bearing firmly toward each other and for drawing said seats surrounding said openings and on said pins against each other when the clamping pressure is applied.

3. A slicing machine comprising a slidable 15 bearing, a support for a carriage on the bearing, a carriage adapted to be releasably supported on said bearing, cooperating bearing surfaces between the carriage and the bearing including a pair of interengaging members for positioning and 20 centering the carriage on one side with respect to the slide bearing, and a clamping member comprising a rotatable member engageable with the carriage and bearing member on the other side of the carriage at a point substantially equidistant 25 from the interengaging centering members for clampingly urging the bearing member and carriage into locking position, said clamping means operating in a direction substantially parallel to the meeting surface of the carriage and bearing, 30 the clamping member drawing the bearing and support toward each other and drawing the seats of the interengaging members against each other when clamping pressure is applied to the clamping member.

35 4. A slicing machine comprising a carriage having substance support bearing members on the carriage below the support, supporting means carried by the bearing members and slidably mounted therein, and a substance supporting 40 member arranged on a side edge of the substance support on the carriage and operatively fastened to the supporting means whereby the supporting member may be moved from a point immediately adjacent the said side edge of the substance support on the carriage to a point remote therefrom, 45 and providing a substance support for supporting substance extending beyond the said edge of the said substance support of the carriage.

5. A slicing machine comprising a carriage 50 having substance support bearing members on the carriage below the support, supporting means carried by the bearing members and slidably mounted therein, and a substance supporting 55 member arranged on a side edge of the substance support on the carriage and operatively fastened to the supporting means whereby the supporting member may be moved from a point immediately adjacent the said side edge of the substance support on the carriage to a point remote therefrom, 60 and providing a substance support for supporting substance extending beyond the said edge of the said substance support of the carriage, the said substance supporting member having its upper supporting surface thereof substantially in the 65 same horizontal plane as the first named substance support.

JOSEPH FOLK.
